SOCKET FOR INK ROLLER

Corson Walter Chase, Oak Park, Ill., assignor to The Goss Printing Press Company, Chicago, Ill., a corporation of Illinois

Application February 18, 1955, Serial No. 489,009

13 Claims. (Cl. 101—348)

The present invention relates to printing presses and more particularly to a socket for mounting ink rollers therein.

It is a general object of the present invention to provide an improved socket for an ink roller which, after initial adjustment, is self-adjusting to accommodate itself to changes in roller diameter due to heat and absorption of ink and which permits substitution of a replacement roller having a different diameter without necessity for readjustment.

It is an object of the present invention to provide an improved socket for an ink roller which enables the roller to bear resiliently and, if desired, with equal force against two ink cylinders laterally spaced from one another.

It is another object of the present invention to provide an improved socket for an ink roller which enables force to be brought to bear resiliently against two ink cylinders, either equally or in predetermined ratio, independently of internal forces such as imposed by gravity or by the pressure of auxiliary rollers and cylinders.

It is a further object of the invention to provide a socket for a printing press roller which may be mounted on the press frame as a unit, requiring only the drilling and tapping of small diameter mounting holes in the frame, and which does not require precise location of the mounting holes.

It is another object of the present invention to provide a socket for an ink roller in which the roller is held captive under operating conditions but which permits the roller to be readily released for cleaning or replacement.

Finally it is an object to provide an improved socket for an ink roller which holds the roller securely, which is free of vibration, which is inexpensive, and which requires a minimum of attention and maintenance.

Other objects and advantages of the invention will become apparent upon reading the attached detailed description and upon reference to the drawings, in which

Figure 1 shows an arrangement of ink rollers and cylinders in a printing press in which the present invention may be employed.

Fig. 2 is a perspective of an ink roller socket constructed in accordance with the present invention, with certain portions broken away or slightly distorted to bring out the details of construction.

Fig. 3 is a top view of the socket in partial section and with the yoke arms swung outwardly incident to releasing the ink roller.

Fig. 4 is a fragment showing the lost motion between the yoke body and yoke arms which is utilized in the locking action.

Fig. 5 is a side elevation of the ink roller socket.

Fig. 6 is a face view of the socket base plate showing the range of adjustment.

Fig. 7 is a vertical section taken along the line 7—7 in Fig. 6.

Fig. 8 shows the range of lateral self-adjustment provided in the ink roller socket exaggerated for emphasis.

2

Fig. 9 is a force diagram showing the forces acting upon the roller mounted in the present socket.

Fig. 9a is similar to Fig. 9, but shows the forces where one of the rollers is omitted.

Fig. 10 is a fragmentary cross section showing a modified spring mount.

While the invention has been described in connection with a preferred embodiment, it will be understood that I do not intend to limit the invention to such embodiment, but intend to cover all modifications and alternative constructions and uses which are included within the spirit and scope of the appended claims.

Turning to Figure 1, an ink roller arrangement indicated generally at 10 is fed by ink from a fountain roller 11 and serves to supply a thin and uniform film of ink to plates mounted on a plate cylinder 12.

Included in the path of ink flow are a feed roller 13 and transfer rollers 14—16, which supply a film of ink to the first ink drum 17. Ink is taken from the ink drum by rollers 18, 19, a portion of this ink film being transferred to a second ink drum 20. From the ink drum 20 the film is transferred to the plate cylinder by form rollers 21, 22. Ink is additionally supplied to the form rollers by auxiliary cylinders 23, 24, respectively, which receive their ink supply directly from the rollers 18, 19, previously referred to. The rollers 18, 19 are mounted in sockets 31, 32, respectively, constructed in accordance with the present invention.

Turning to the perspective of the socket 31 shown in Fig. 2, it will be seen that it includes a base plate 33 and a yoke body 34 carrying yoke arms 35, 36. The yoke arms straddle and support a bearing capsule 40 containing an anti-friction bearing 41 into which is telescoped the shaft 42 of the ink roller 18. Under normal operating conditions the yoke arms 35, 36 form a rigid unit with the yoke body 34.

Means are provided for mounting the yoke body 34 in the base plate 33 for rocking movement about an axis which extends at right angles to the axis of the roller. For this purpose the yoke body 34 includes a pair of short rearwardly extending arms 45, 46. The arms are pivoted on pins 47, 48 which are pressed into place in the base plate. To enable the pins to be removed they are tapped at 49, 50 for pull screws. For recessing the arms 45, 46 in the mounting plate, the plate has deep slots of arcuate contour milled in its face, the slots being indicated at 51, 52. The above arrangement permits the yoke to be rocked upwardly and downwardly through a relatively large angle relative to the press frame. For the purpose of exerting a biasing force upon the roller, the upper portion of the yoke body 34 is engaged by springs 55, 56, which are seated in pockets 57, 58 in the base plate. Adjusting screws 59, 60 are provided for adjusting the pressure exerted by the springs 55, 56, the adjusting screws engaging pilot discs 61, 62 mounted on the outer ends of the respective springs. The yoke body 34 may be bodily rocked against the spring pressure by means of a bar 63 or other suitable tool inserted in a central aperture 64 at the top of the yoke body.

In accordance with the present invention, the arms 35, 36 are mounted for outward swinging movement away from the bearing capsule 40 about axes arranged generally at right angles to the rocking axis of the yoke body, to free the bearing capsule 40 so that the roller 18, with bearings attached, may be removed from the press. Thus, as shown in Figs. 2 and 3, the arms 35, 36 are mounted for pivoting on pins 71, 72, respectively, which extend through a support 73 on the yoke body 34. Projecting inwardly at the ends of the arms 35, 36 are trunnion pins 75, 76. For enabling pivoting engagement between the pins 75, 76 and the bearing capsule 40, the capsule is provided with trunnion pockets 77, 78, located

respectively at diametrically opposite points. As will be noted in the drawings, the pivoting axis defined by the pins 75, 76 is not only perpendicular to the roller axis but is parallel to the rocking axis of the yoke body. As a result, the roller 18 is guided along a straight-line path of movement indicated at 80 (Fig. 8) between the two cylinders 17, 20 with which it rides in contact.

In accordance with one of the features of the present invention, novel means are provided for locking the yoke arms 35, 36 in place under normal running conditions, while permitting the arms to swing outwardly away from the bearing capsule when the roller reaction pressure is released. In the present instance this is accomplished by making the arms axially slidabale on their pivots and by providing detent surfaces on flats on the arms 35, 36, which mate with registering flats on the yoke body when the arms are in their normal operating position.

Referring to Fig. 4, the arm 35 has an angled flat 81, which mates with a flat 82 milled on the lower edge of the support 73 on which the arms are mounted. When the roller is operating normally under pressure exerted by the springs 55, 56, the reactive pressure of the cylinders 17, 20 presses upwardly on the ink roller 18. Such reactive pressure is transmitted to the trunnion pins by the bearing capsule 40, thereby urging the arms 35, 36 vertically upward as viewed in Fig. 2 and seating the flats 81, 82 against one another. The flats not only lock the arms against outward movement but insure that the arms are solidly seated and precisely positioned as long as reactive pressure is exerted against the roller. When it is desired to remove the roller for purposes of cleaning or adjustment, a bar or similar tool 63 is inserted into the opening 64 in the yoke body. The leverage provided makes it an easy matter to tilt the yoke body into the retracted position shown in Fig. 4 against the compressive force of the springs 55, 56. This causes dropping movement of the arms 35, 36 relative to the yoke body, which separates the flats 81, 82 so that the parts occupy the positions shown in the fragmentary view, Fig. 4. With the flats separated, the arms may be pivoted outwardly away from the bearing capsule, as illustrated in Fig. 3, and the roller 18 and the connected bearing capsule may then be lifted clear without obstruction.

Replacement of the roller is accomplished simply by reversing the procedure. The roller 18 is placed in its normal position between the adjacent cylinders and the yoke body 34 is rocked backwardly, compressing the springs 55, 56. This enables the arms 35, 36 to be lifted on their pivots and swung inwardly for engagement of the trunnion pins with the trunnion pockets 77, 78. Subsequent releasing of the spring pressure causes seating of the flats and results in locking of the socket for continued operation. While it is true that rocking of the yoke is accompanied by slight relative axial movement between the roller and the yoke, such relative movement does not interfere with the action of the socket and is absorbed by relative movement between the bearing and bearing capsule 40.

In accordance with one of the more detailed features of construction, the mounting plate 33 of the socket is arranged for pivoting about a central axis and means are provided for clamping the mounting plate in a desired angular position. This is accomplished as shown in Figs. 6 and 7 by a central pivot in the form of a stud 85 which is screwed into the back of the base plate along an axis which is generally alined with the roller axis when the roller occupies its normal running position. The stud 85 extends through a suitable aperture bored in the frame indicated at 86 and terminates in a nut 87 so that the base plate may pivot through a substantial angle 88 (Fig. 6). The base plate is secured in the desired position by means of screws 91, 92, 93 which are received in arcuate slots cut in the base plate and centering about the stud 85.

Means are further provided for enabling the roller 18

to move broadwise over a small range relative to the mounting plate 33 and the press side frame to which it is mounted. In the present embodiment this is accomplished by providing radial clearance between the ends 5 of the trunnion pins 75, 76 bottoms of the pockets in the bearing capsule 40, the clearance being indicated at 94, 95 in Fig. 8. It will, of course, be understood that a substantially identical socket of the type described is employed at each end of the roller 18. The roller is therefore free to move over a lateral range as indicated by the dotted outlines 96, 87 (Fig. 8) to find its own seated position on the cylinders 17, 20.

One of the primary advantages of the above arrangement is that it enables the roller 18 to apply forces to be applied to the cylinders 17, 20 which are either balanced or which are proportioned in a predetermined ratio even when the roller is acted upon by external forces such as gravity and auxiliary rollers and even though a roller of slightly different diameter may be substituted. This will be made clear upon referring to Fig. 9 which shows a vector diagram of the forces acting upon the roller 18. One of the forces is of course, the socket spring force which will be assumed to have the magnitude and direction 98. Another is the known force of gravity acting downwardly upon the roller and indicated at 99. A third is the force 23-18 exerted upon the roller by the auxiliary cylinder 23, the magnitude of which is known in a particular instance and which acts along a line which intersects both of the centers of rotation.

Opposing the above three forces are the reactive forces of the two cylinders 17, 20 indicated at 17-18 and 20-18 respectively. Both of these forces also act along lines intersecting the centers of rotation.

With a spring force 98 it will be apparent that the force 35 between the roller 18 and cylinder 17 is about one and one-half times as great as the force between the roller and cylinder 20. Such ratio will be maintained even if the roller 18 changes dimension due to heat or ink absorption and even if the roller 18 is substituted by one 40 having a slightly different diameter. If it is desired to apply balanced forces against the two cylinders for creation of equal flats, the ink roller sockets, one at each end of the roller, are rotated through an angle A and the spring pressure is reduced to provide a spring vector 98a. 45 The limited amount of lateral play of the roller 18 provided by the lost motion between the yoke and bearing capsule is desirable since it gives the roller freedom to assume a desired equilibrium position between the two cylinders under all conditions within the range of adjustment. Once adjusted the settings need not be changed, if desired, over the life of the press.

Where the rollers 23, 24 are not present, a simplified force condition obtains as in Fig. 9a where the vector 23, 18 is omitted.

One important practical advantage of the present device is that the holes for the mounting screws need not be located with a high degree of precision and both installation and maintenance may be reduced to a minimum.

Under some conditions where it is desired to apply 60 only a light force the weight of the roller 18 and the force exerted by the auxiliary cylinder 23 may, in combination, be excessive or the weight acting alone may be excessive. To take care of this situation the spring 55, 56 may be anchored so that force may be exerted either 65 in tension or compression. For example, the springs may be anchored as shown in Fig. 10 where corresponding parts are indicated by corresponding reference numerals. As shown here, the ends of each spring are secured respectively to the mounting plate and yoke, the type of mounting being referred to for convenience as "two-way" anchoring. At the yoke end this is accomplished by using an adjusting screw 59a which is captive in the pilot disc 61a. When the springs are in tension the net effect is to provide a force which subtracts from rather than 70 adding to the forces existing at the flats.

While the invention has been described in connection with only one of the rotating elements in the path of ink flow, namely, roller 18, it will be apparent to one skilled in the art that the invention is fully applicable to all of the resilient rollers. The invention is, furthermore, applicable, to the mounting of steel cylinders where the various features including the adjustment of the direction of forces and ease of removal and replacement are desirable. Thus, in the following claims the terms "rollers" and "cylinders" are not necessarily limited to rubber-covered and hard-surfaced elements, respectively, but refer more generally to cylindrical ink-transferring elements regardless of covering.

I claim:

1. In a printing press the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft, said yoke having a hinge connection with said frame and arranged perpendicular to the roller axis at one end and having a pivoted connection with said bearing at the other end, means for biasing the yoke relative to the frame, the hinge connection between the frame and the yoke having provision for changing the direction of the hinge axis with respect to the axis of the roller to vary the direction of the force applied to the roller by the yoke so as to proportion the forces applied by the roller to the individual ink cylinders.

2. In a printing press the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft, said yoke having a hinge connection with said frame at one end and having releasable arms at the other end for pivotally engaging the bearing, and means for biasing the yoke relative to the frame, the hinge connection between the frame and the yoke having provision for changing the direction of the hinge axis relative to the axis of the roller to vary the direction of the force applied to the roller by the yoke and said yoke providing a lost motion connection between the bearing and said side frame to permit the roller to establish an equilibrium position relative to the cylinders.

3. In a printing press the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft, said yoke having a hinge connection with said frame at one end and having means for pivotally engaging the bearing at the other end, a spring for biasing the yoke relative to the frame, said spring being adjustably mounted to permit development of tension and compression therein depending upon the adjustment, said yoke being so constructed and arranged as to permit limited broadwise movement of the roller in the direction of the hinge axis so that the roller is free to such an equilibrium position relative to the cylinders.

4. In a printing press, the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft and having opposed arms for straddling said bearing, means including trunnion pins for pivotally connecting said arms and the respective sides of said bearing, and means providing a hinge connection between the yoke and the side frame so oriented that said roller is guided along a path of movement between the spaced cylinders, said arms being arranged on said yoke for movement between a normal position in which the

trunnions are engaged and a second position in which the trunnions are disengaged for removal of the roller and bearing.

5. In a printing press, the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft and having opposed arms for straddling said bearing, means including trunnion pins for pivotally connecting said arms and the respective sides of said bearing, means providing a hinge connection between the yoke and the side frame so oriented that said roller is guided along a path of movement between the spaced cylinders, said arms being hinged on said yoke for outward swinging movement between a normal position in which the trunnions are engaged and a roller-releasing position in which the trunnions are disengaged, and disengageable means for locking the arms in the normal position.

6. In a printing press, the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft and having opposed arms for straddling said bearing, means including trunnion pins for pivotally connecting said arms and the respective sides of said bearing, means providing a hinge connection between the yoke and the side frame so oriented that said roller is guided along a path of movement between the spaced cylinders, at least one of said arms being pivoted on said yoke for movement between a normal position in which the trunnions are engaged and a roller-releasing position in which the trunnions are disengaged, and means actuated by the reaction force transmitted to said one arm from said roller for locking the arm in its normal position.

7. In a printing press, the combination comprising a side frame, a pair of ink cylinders laterally spaced from one another, an ink roller having a shaft and arranged to engage said ink cylinders, a bearing surrounding the end of said shaft, a yoke extending generally in the direction of the axis of said shaft and having opposed arms for straddling said bearing, means including trunnion pins for pivotally connecting said arms and the respective sides of said bearing, means providing a hinge connection between the yoke and the side frame so oriented that said roller is guided along a path of movement between the spaced cylinders, pivot connections on said yoke for pivoting the arms thereto for movement between a normal position in which the trunnions are engaged and an outwardly swung position in which the trunnions are disengaged, means including a spring coupled to said yoke for biasing the roller into engagement with the cylinders, and means including detents at said pivot connections responsive to the biasing force for locking the arms in their normal position.

8. In a printing press, the combination comprising a side frame, a pair of ink cylinders laterally spaced from one another, an ink roller having a shaft and arranged to engage said ink cylinders, a socket base having a central pivot connection with the side frame together with manual means for clamping the base in a desired orientation relative to the side frame while maintaining the same parallel thereto, a bearing generally aligned with the pivot on said base and axially spaced from the base for receiving said shaft, and a yoke pivoted at its ends to said base and said bearing respectively about axes which are parallel to one another and at right angles to the roller axis to provide bodily movement of the bearing so that the roller is guided along a plane of movement between said spaced cylinders.

9. In a printing press, the combination comprising a side frame, a pair of ink cylinders laterally spaced from

one another, an ink roller having a shaft and arranged to engage said ink cylinders, a base plate having a central pivot connection with the side frame, manually operated means for locking the base plate in a desired orientation relative to the side frame, a bearing generally aligned with the pivot on said base plate and axially spaced from the base plate for receiving said shaft, a yoke pivoted at its ends to said base plate and said bearing respectively to provide bodily movement of the bearing so that the roller is guided along a straight-line path of movement between said spaced cylinders, and a spring interposed between said yoke and base plate for biasing the roller.

10. In a printing press, the combination comprising a side frame, a pair of ink cylinders laterally spaced from one another, an ink roller having a shaft and arranged to engage said ink cylinders, a bearing telescoped over the end of said shaft, a yoke extending along the axis of said shaft and having arms straddling said bearing, aligned trunnion pins extending inwardly from said arms, said bearing having outwardly facing pockets for receiving said trunnion pins, said yoke being hinged to the side frame so that said roller is guided along a path of movement between the spaced cylinders, the root diameter defined by said pockets being less than the spacing of said trunnions so that the roller is free to move broadwise through a limited range to assume an equilibrium position between said cylinders.

11. In a printing press, the combination comprising a side frame, a pair of ink cylinders laterally spaced from one another, an ink roller having a shaft and arranged to engage said ink cylinders, a bearing telescoped over the end of said shaft, a yoke having a yoke body and having opposed arms extending along the axis of said shaft and having normal pivoted engagement with said bearing, a base plate on the side frame having a pivoted mounting for said yoke so arranged that the roller is guided for bodily movement along a centered path of movement relative to said ink cylinders, a spring interposed between said base plate and said yoke for causing the roller to bear against said cylinders with resilient pressure, said yoke arms having pivot connections with said yoke body enabling them to be swung laterally away from said bearing, cooperating flats on said yoke body and on the re-

spective arms aligned with one another when the arms are in normal position, said pivot connection including provision for lost motion and said flats being so arranged that the lost motion is taken up incident to application of pressure from said spring upon said roller to produce seating of said flats lockingly against one another while permitting the flats to be unseated and the arms to be swung outwardly upon manual retraction of the yoke body against the force of the spring for removal of the bearing and roller.

12. In a printing press, the combination comprising a side frame, a pair of ink cylinders laterally spaced from one another, an ink roller having a shaft and arranged to engage said ink cylinders, a bearing surrounding the end 15 of said shaft, a yoke extending generally in the direction of the axis of said shaft, said yoke having a hinged connection with said frame at one end on an axis perpendicular to the roller axis and having means for pivotally engaging the bearing at the other end, means including 20 a spring for biasing the yoke relative to the frame, the ends of said spring being captive in said yoke and frame respectively and having provision for adjusting the effective length thereof so that the spring applies either tension or compression to the yoke, depending upon the adjustment.

13. In a printing press, the combination comprising a side frame, a pair of ink cylinders laterally spaced from one another, an ink roller having a shaft and arranged to engage said ink cylinders, a bearing surrounding the end 30 of said shaft, a yoke having a hinged connection with the frame and having a hinged connection with the bearing, said hinge connections being spaced from one another in the direction of the roller axis and having axes which are 35 parallel to one another and at right angles to the roller axis, and means including an adjustable spring acting upon the yoke and reacting against the frame for biasing the roller against said ink cylinders.
